DOUBLE-ACTING HYDRAULIC PUMP

Fiorindo D. Coletta, Alfredo Chaves, Brazil

Application June 18, 1934, Serial No. 731,147
In Brazil July 29, 1933

3 Claims. (Cl. 103—146)

The present invention relates to pumps of the hydraulic type, and has for an object to provide a pump of large capacity relative to the size of the pump, and to provide a pump of but few 5 movable and separate parts.

The present invention provides a pump having two semi-spherical parts which, when united, form a hermetically sealed spherical chamber or casing in which is mounted on a single axis but 10 one piston so disposed and sealed in the chamber as to rock on its axis and effect a double pumping action.

The present invention is an improvement on semi-rotative pumps having metallic shovel 15 blades of the type known as the vane or wing pump as these blade pumps are widely used on account of their low cost, but lack capacity and their effective operation is of but short duration. Many prior attempts have been made to 20 improve this type of pump but the suggested changes have not warranted their adoption in that they failed their objects or unwarrantedly increased the size and cost of the pump.

The present pump overcomes all of the prior 25 disadvantages with a construction which is of utmost simplicity and extremely accurate in operation, which is strong and durable and which may be operated with a minimum of effort.

With the foregoing and other objects in view, 30 the invention will be more fully described hereinafter, and will be more particularly pointed out in the claims appended hereto.

In the drawings, wherein like symbols refer 35 to like or corresponding parts throughout the several views,

Figure 1 is a front elevation of the pump of this invention.

Figure 2 is a section taken through the same 40 on the line 2—2 of Figure 1.

Figure 3 is a section taken axially at right angles to and on the line 3—3 of Figure 2.

Figure 4 is a detail top plan view of the single 45 piston and valve unit.

Figure 5 is a detail top plan view of the sector 50 with its valves.

Figure 6 is a bottom plan view of the same.

Figure 7 is a detail perspective view of the 55 partition packing for the piston.

Figure 8 is a detail sectional view through the piston body.

Figure 9 is a detail sectional view through the piston nut and packing, and

Figure 10 is a detail enlarged view, partly in 55 section, showing a slightly modified form of

handle and mounting therefor on the rocker shaft.

Referring to the drawings, 15 and 16 designate the opposed sections or parts of the pump casing. These parts are of semi-spherical construction and the parts 15 may be provided at the bottom and top respectively with inlet and outlet connections 17 and 18 for attachment to pipes or the like through which liquid is to be pumped. The casing parts 15 and 16 are flanged and held together by bolts 19, as shown in Figure 1, and any suitable packing may be interposed to effectively seal the joint between the parts. The parts may be of any exterior configuration but interiorly they provide a substantially true spherical chamber. Centrally disposed in the parts 15 and 16 are journal bearings 20 and 21 which are coaxial with each other and with the transverse axis of the spherical chamber. A rocker shaft 22 has bearing at one end in the bearing 20 which is closed at its outer end and at its other end passes through the bearing 21 and beyond the same for receiving a handle 23. A gland or packing 24 seals the outer end of the shaft 22 in the bearing 21. A single piston of the rocking type is mounted on the shaft 22 within the spherical chamber and has a body portion 25, as shown in detail in Figure 8, of annular form with exterior threads and an outstanding annular shoulder 26 at the base of the threads.

Extending diametrically across the lower closed end of the body portion 25 is a tubular rib 27 shaped at opposite ends to conform to the spherical contour of the inner wall of the casing chamber and which has a flat upper wall 28 for contact with a flat face 29 on the rocker shaft 22. The shaft 22 extends at its intermediate portion through the rib 27 and is held from shifting by shoulders 30 suitably formed on the shaft, one of which may be struck up after the rib is in place.

The piston body 25 has a valve port 31 at each side of the rib 27 and a flap valve 32 is provided for each port 31. The valves 32 comprise flat plates normally lying on the upper face of the piston body 25 and have pairs of arms 33 which converge upwardly and overlap at their upper ends and are connected together and pivotally supported on a pivot rod 34 which also passes through a centrally disposed post 35 in the piston body 25. The annular wall of the piston body 50 has an opening 36 in one side thereof in line with the opening in the post 35 to admit easy assembling of the valves 32 in the piston body. A ring nut 37 is threaded about the piston body 25, and has an upwardly tapering and rounded periph-

eral surface, and fits within an annular washer 38 which is flexible and of leather, rubber or of other material or composition suitable for the purpose. The base of the washer 38 is turned 5 inwardly as shown in Figure 9 and is clamped against the annular shoulder 26 of the piston body by turning the nut 37 down toward the same.

The peripheral surface of the nut 37 is so rounded as to hold the upstanding portion of the washer 38 to the shape of the spherical inner wall of the casing chamber to seal the piston thereagainst. As the rib 27 extends across the bottom of the piston 25 the latter is supported above the central axis of the spherical casing and therefore the 10 piston has not only a pivotal movement but also a bodily movement when reciprocated or swung back and forth. A substantial fluid chamber is thus provided beneath the piston and ample room is provided for a valve and partition structure for 15 the casing.

Within the bottom of the pump casing is disposed a sector-shaped valve block 39 which is hollow and has its base portion lowermost and communicating with the intake connection 17 of 20 the valve casing. The bottom wall of the block 39 is apertured for this purpose, as shown particularly in Figures 2 and 3.

It will be noted from Figure 2 that the sector valve block is elongated in the direction of the 25 axis of the shaft 22 and that it is rounded or curved at opposite ends to fit snugly against the interior wall of the casing. Screws 40 pass through the lower walls of the casing and engage the valve block to hold it in place.

30 The opposite upwardly converging sides of the valve block 39 are provided with valve ports 41 and 42 which are normally covered by check or flap valves 43 which normally rest against the inclined sides of the valve block over the ports 44 and 42 and which have arms 44 pivotally connected at 45 to lugs 46 which extend outwardly in opposite directions from the apex portion of the valve block. At the apex, the valve block is provided with a longitudinal channel 47 which 35 opens upwardly through the block and faces the lower side of the rib 26 carried upon the shaft 22. A channel packing 48 in the form of a flexible sheet or strip overturned upon itself is secured at its overturned portion in the channel 47 and has its free edge portions flaring upwardly and bearing against the lower rounded side of the tubular rib 27 so that the packing 48 and the valve block 39 provide a partition which is disposed intermediate the lower 40 end of the casing and which is sealed against the lower axial portion of the piston.

In operation, the handle 23, or other suitable 45 operating device connected to the shaft 22 is reciprocated back and forth to rock the shaft 22 and the piston 25 carried thereby. As one side of the piston 25 is swung upwardly, as shown in Figure 3, the suction created beneath said side of the piston raises the adjacent check valve 43 and draws liquid upwardly through the 50 intake 17 of the casing and into and through the valve block 39, the fluid passing outwardly through the port 41 and into the lower or intake chamber of the casing.

During this swinging movement of the piston 25 the opposite side thereof is swung downwardly whereupon the liquid entrapped in the 55 opposite intake chamber of the pump holds the flap valve 43 to its seat to close the port 42 and also flows upwardly through the adjacent opening 31 in the piston body and raises the

flap valve 42 so that the liquid passes into the upper or outlet chamber of the pump. As soon as the piston 25 is rocked in the opposite direction the liquid in the outlet chamber of the pump is forced upwardly through the outlet connection 18 as the flap valve 32 at the lower side of the piston is closed by the weight of the liquid and the flap valve 43 of the valve casing is also closed by the weight of the liquid, the piston at its lower side enlarging the adjacent intake chamber and opening the adjacent flap valve 43 for drawing in an additional quantity of liquid through the valve port 42 of the casing.

As the casing is of spherical form the pump is of relatively large capacity as the entire cross 10 sectional area of the chamber of the pump is utilized as the intake and outlet chambers. The single piston also occupies a minimum of space and the valve arrangement of both the piston and the casing is such that the valves are positive in operation and the pivots and mountings for the valves are of simple construction and provide few working parts.

20 It will also be noted that the parts may be quickly and easily assembled and that access 25 may be readily had to the interior of the pump for renewing the washer 38 when worn.

It is obvious that various changes and modifications may be made in the details of construction and design of the above specifically described embodiment of this invention without departing from the spirit thereof, such changes and modifications being restricted only by the scope of the following claims.

25 A slight modification is shown in Figure 10 35 wherein the shaft 22 has a handle 49 with a hub 50 fitting over the end of the shaft and locked thereto by a key 51. A set screw 52 may be threaded through the hub 50 to bind 40 against the shaft 22 and hold the handle firmly in place.

What is claimed is:—

1. A double acting hydraulic pump comprising a casing composed of a pair of mating sections each having a semi-spherical chamber portion therein, a shaft journaled in said casing sections co-axial to the chamber, a piston fitting in the chamber and connected at its intermediate lower portion to the shaft, means for rocking the shaft and piston, a post rising from the central portion of the piston, a pivot rod carried by the post, a pair of flap valves pivotally mounted on the rod and seated against the top of the piston at opposite sides of the post and the shaft, said piston having valve ports therethrough beneath the flap valves, a hollow valve block seated in the bottom of the chamber and having valve ports in opposite sides, flap valves pivotally mounted on the valve block for covering said ports, and a sealing washer carried on the upper end of the valve block for engaging the piston and sealing the block thereagainst to divide the lower portion of the chamber into opposed sections, said casing having an inlet connection opening into the valve block and having an outlet connection leading from the chamber above the piston.

2. A double acting hydraulic pump comprising a casing having a spherical chamber therein with an inlet leading to the bottom of the chamber and an outlet leading from the top thereof, a rocker shaft journaled in the casing coaxial with the chamber, a piston fitting in the chamber and having a rib across its lower end keyed to the shaft to rock the piston with the shaft, a 70 75

clamping nut carried by the piston, a sealing washer carried by the piston beneath the nut and having an outer portion enclosing the nut, the exterior surface of the nut conforming substantially to that of the inner wall of the spherical casing for supporting the washer in sealing engagement therewith, said piston having valve ports therethrough at opposite sides of the rib, a pair of flap valves for said ports, a common pivot for the flap valves carried by the piston, a valve block mounted in the lower end of the chamber and communicating with the intake connection of the casing and having opposed valve ports opening into the chamber beneath the opposite sides of the piston, a sealing washer carried by the valve block bearing against the rib of the piston to seal the valve block thereagainst, and flap valves pivotally mounted on the valve block for closing said ports therein.

20 3. A double acting hydraulic pump comprising

a casing having a spherical chamber therein, a shaft mounted axially in the chamber and adapted to be reciprocated, a piston sealed in the chamber and having a transverse rib across its bottom engaging the shaft for supporting the piston above the shaft and for rocking movement with the shaft, and having valve ports at opposite sides of the rib, said piston also having an intermediate upstanding post, valves mounted on the post of the piston at opposite sides of the rib to control the valve ports, a valve block mounted in the bottom of the chamber and sealed against said rib, and valves carried by the valve block opening into the chamber beneath the piston at opposite sides of the partition, said casing having an inlet connection opening into the valve block and having an outlet connection leading from the casing chamber above the piston.

FIORINDO D. COLETTA.
